UNITED STATES PATENT OFFICE.

THOMAS CAMPBELL FUTERS AND CHARLES JEFFREYS FORRESTER, OF MANCHESTER,
ENGLAND.

TEE FOR GOLF BALLS.

Application filed July 24, 1925. Serial No. 45,938.

To all whom it may concern:

Be it known that we, THOMAS CAMPBELL FUTERS and CHARLES JEFFREYS FORRESTER, subjects of the King of Great Britain, and residents of Harp Street, Old Lane, Higher Openshaw, Manchester, in the county of Lancaster, England, have invented certain new and useful Improvements Relating to Tees for Golf Balls, of which the following is a specification.

This invention relates to tees for golf balls and has for its object to provide an improved form of tee.

In accordance with our invention, the stem of the tee which is to be pressed into the ground is made ribbed or fluted, the ribs or flutes tapering away towards the point of the stem. The said ribs or flutes may be straight or spiral and extend from the top to the bottom of the tee. They serve to obtain a good hold upon the ground into which the tee is pressed so as to give stability to the device. The top of the tee is made of saucer shape to receive the ball. The complete tee may be made of aluminium or other material; the top being hollowed out to saucer-like shape to receive the golf ball. Preferably the fluted stem is made of hard or vulcanized rubber and the top of soft rubber, the two parts being united by heat

and pressure in a mould. Alternatively, the stem only may be made of metal, and the saucer portion be made of rubber having a sleeve-like extension into which the stem fits.

A tee constructed in accordance with our invention is illustrated in the accompanying drawing in which Figure 1 is an elevation of the fluted metal stem *a* with the rubber cup *b* in section. Figure 2 is a sectional plan on the line AB of Figure 1. The cup *b* is sprung over the head *c* formed integrally with the stem *a* and protects the club against marking; also it forms a holder for the ball.

Figure 3 shows a tee made of a hard rubber stem and a soft rubber top united by heat and pressure in a mould.

We claim:

1. A tee for golf balls comprising a tapered stem having a plurality of flutes therealong and a top of saucer shape central with the stem, as set forth.

2. A tee for golf balls as claimed in claim 1, in which a rubber saucer like top is secured to the fluted stem, as set forth.

In testimony whereof we have signed our names to this specification.

THOMAS CAMPBELL FUTERS.

CHARLES JEFFREYS FORRESTER.
